FIRE PROTECTION STANDPIPE SYSTEM

William F. Conran, Brooklyn, N. Y.

Application June 29, 1931, Serial No. 547,617

13 Claims. (Cl. 169—16)

This invention relates to standpipe systems for fire-protection in buildings. Systems of this general character are disclosed in my Patents Nos. 816,152, 1,156,978 and 1,253,005 and in certain copending applications.

In such standpipe systems, the standpipe is provided with nozzles at the several floors and with valves for opening and closing communication between the nozzle branches and the interior of the standpipe, these valves being controllable independently from a central control station in the lower part of the building. The standpipe with its nozzles may be raised and lowered, or it may be turned, or it may be capable of both of these movements. Again, the individual nozzles may be pivoted so that their vertical deflection can be changed or so that they can be oscillated up and down, such movements of the nozzles being also individually controllable from the control station.

In addition to the nozzles carried by the standpipe, it is important to provide hose outlets and valves at the several floors. The hose can be used by a person on the floor where a fire may occur. When it proves impossible to subdue the fire at close quarters the person operating the hose may be compelled to seek safety without closing the hose valve, and it then becomes impossible to deliver an adequate stream from the standpipe nozzle at the floor, or at any floor, under remote control from the control station, because the open hose valve robs the pressure.

One of the objects of this invention is to provide means for automatically closing the outflow through the hose connection when the nozzle valve at the same floor is opened from the control station. This is preferably accomplished by the provision of a remote-control valve in combination with seats against which it can close alternately in two positions. In the normal position of this valve it closes against a seat through which water must pass to the nozzle and is away from a seat through which water must pass to the hose valve. When the remote control valve is opened in respect to the nozzle it is closed in respect to the hose valve. Manifestly a combination of valve elements subject to the same operation of the remote-control means will serve the same purpose as a double-faced valve.

Another object of the invention is to relieve the interior of the standpipe of obstruction by the control lines and at the same time adequately to protect these control lines.

Another object is to reconcile the external disposition of the control lines and their protective enclosures with movability of the standpipe. Special bearings are provided in this connection for laterally supporting the standpipe and for affording passage of the control lines and their

enclosures without interfering with the movability of the standpipe.

Still another object of the invention is to provide the standpipe with nozzles which can be swung in horizontal arcs relatively to the standpipe, so as to turn the streams in any lateral direction or to cause them to sweep back and forth over an area. For such operation the nozzles are controllable independently from the remote control station.

Other objects and features of the invention will become apparent from the drawings and from the more detailed description of the illustrative embodiments shown therein.

In the said drawings:

Fig. 1 is an elevation of a standpipe system constructed in accordance with the invention, parts being broken out for economy of space and only two floors being illustrated on which the nozzles and hose valves are shown;

Fig. 2 is a view on an enlarged scale, parts being in elevation and parts in section and looking in the same direction as in Fig. 1;

Figs. 3, 4 and 5 are cross-sectional views taken, respectively, on the lines 3—3, 4—4 and 5—5 of Fig. 2;

Fig. 6 is a fragmentary detail longitudinal section taken on the line 6—6 of Fig. 3;

Fig. 7 is a view similar to Fig. 1 showing a somewhat different form of the invention;

Fig. 8 is a detail cross-sectional view taken on the line 8—8 of Fig. 7, parts being in elevation;

Fig. 9 is a cross-sectional view taken on the line 9—9 of Fig. 7;

Fig. 10 is a fragmentary longitudinal sectional view taken on the line 10—10 of Fig. 9;

Fig. 11 is a cross-sectional view taken on the line 11—11 of Fig. 7; and

Fig. 12 is a fragmentary longitudinal sectional view taken on the line 12—12 of Fig. 11.

Reference will now be had to Figs. 1 to 6. The standpipe 2 comprises a number of pipe sections 3 joined together by the nozzle fittings 4 and the operating station fitting 5. The bottom pipe section 3 is closed by a cap 6 carrying the supporting pivot 7, which is rotatably supported in a bearing pedestal 8. The standpipe extends upwardly through the floors 9 of the building and receives lateral support in the bearings 10, which will be described more in detail later on.

A fitting 11, provided with the usual Siamese connection 12, forms the inlet to the standpipe, and a lever 13 at the operating station provides means for manually turning the standpipe, to direct the stream at any floor or floors in any lateral direction or to cause it to sweep back and forth over an area.

The form of the nozzle fittings 4 and the method of attaching and operating the nozzles, may be widely varied, and it is to be understood that

while only two such fittings are illustrated in Fig. 1, they are to be located at intervals throughout the length of the standpipe to protect the several floors or stories. Each fitting is shown with a 5 branch 14 bifurcated at its outer end to provide a pivoted connection for the nozzle 15.

The branch 14 contains spaced, opposed seats 16 and 17, against which a disc valve 18 can close alternately. Applied to an extension 20 of the 10 branch 14 is a hose connection having a manually operated hose valve 21. The hose valve connection 20 is back of the seat 17. To it is attached a fire-hose 22 carried by a hose rack 23, which may be supported on the standpipe or on 15 a wall adjacent the standpipe. For clearness of illustration the hose rack has been shown high up, but that is not necessary.

The valve 18 is on a stem 24, passing through a stuffing-box 25 in one head of a cylinder 26 20 which forms a cover for the extension 20. A piston 27 attached to the other end of stem 16, to work in the cylinder 26, provides for operation of the valve 18.

A spring 28 acting on the piston urges the 25 valve 18 to the seat 16, against which it will also be held by water pressure in the standpipe, and the valve is moved away from said seat and against the seat 17 by the admission of pressure fluid below the piston through the control pipe 29. It will be apparent from inspection of Fig. 2 30 that the valve 18 in the normal position shown in this view will close communication between the standpipe and the nozzle and permit the standpipe fluid to be supplied to the hose valve 21.

35 It will likewise be apparent that when fluid pressure is supplied to the cylinder 26 under the piston 27 the disc valve 18 will be forced against the seat 17 and communication will be closed between the standpipe and the hose valve and established between the nozzle 15 and the standpipe. Thus it is impossible for standpipe fluid to be supplied simultaneously to the hose valve and to the nozzle. In consequence, the important result is obtained of insuring full water 40 pressure for either the hose 22 or the standpipe nozzle 15, depending upon which is in use. When a person on a particular floor, who has been trying to extinguish a fire with the hose, is forced to drop it and seek safety, the supply of water is automatically suspended to the hose, as soon as the nozzle is brought into action by remote control, thus making certain that the maximum pressure will be effective at the nozzle 15 and not be wasted through the open hose valve.

45 Means are preferably provided for swinging the nozzle 15 in a vertical plane, and it is to be understood that the mechanism illustrated for accomplishing this purpose is indicative of only one form of such means that may be employed. The elevation or depression of the nozzle, or 50 oscillation thereof, is controlled from the operating station.

60 In the particular construction illustrated, an arm 31 extending from the branch 14 carries a cylinder 32, in which is a piston 33. Its piston rod 34 extends through a stuffing-box and is connected to the nozzle by a link 35. Operating pressure fluid is supplied to the cylinder 32, under piston 33, by a control pipe 36.

65 In a number of my former disclosures, the fluid-pressure control lines were disposed inside of the standpipe. In my Patent No. 816,152 the control pipes were outside of the standpipe, but 70 the awkwardness of such an arrangement in con-

nection with a standpipe which was to be movable rotatably or vertically, or both, as well as the danger of injury to such small control pipes, caused me thereafter to conduct them inside the standpipe, except where it was necessary for them 5 to emerge. Mechanically, that plan is excellent, and it gives protection to the control lines, but these advantages are secured at the expense of obstructing flow of the fire-fighting fluid in the standpipe and of making access to the control lines difficult, either for inspection or for repair. One of the objects of the present invention 10 is to combine the advantages of these two different types of constructions, without the disadvantages of either. The control pipes are carried with and outside of the standpipe, but in such a way as not to interfere with the movement of the standpipe or with the provision of lateral support direct to the standpipe, and the control pipes are housed and protected, but in such a 15 way that they are accessible. Furthermore, the openings through the floor are effectively closed so as to prevent the spreading of fire from one level to another by flue action.

The control pipes 29 and 36 are preferably 25 bunched together in groups extending close along the outside of the standpipe. There may be one, two or several of these groups, depending upon the number of control lines and the number of floors the standpipe is to protect. As illustrated, 30 the control lines 29 for the nozzle valves 18 are grouped at one side of the standpipe, and the control lines 36 for moving the nozzles relatively to the standpipe are grouped at the opposite side of the standpipe. If movement of 35 the standpipe nozzles about their individual pivots should not be required, the control lines 36 can be omitted. On the other hand, either group of control lines may be split up into smaller groups.

The control lines extend downwardly to the 40 operating station, where they enter the standpipe to receive fluid under pressure and adjacent this point they are provided with three-way valves 37.

A preferred form of means for protecting the 45 external control lines will now be described. The nozzle fittings 4 have ears 40-40 at their upper parts and other ears 41-41 at their lower portions. These ears are apertured for the free 50 passage of the control lines. The upper ears 40 are counterbored for the reception of the lower ends of tubular enclosures 42. The lower ears 41 have threaded openings which receive externally threaded bushings 43. These bushings 55 extend below the ears 41 in the form of a nut and accommodate the upper ends of the sleeves 42. By rotating the bushing 43 until the threaded part is out of engagement with the threaded ear 41, the bushing can be dropped 60 and the annular enclosure members 42 can be freed from the ears. In this manner effective protection means is provided for the control lines between the fittings and also one that readily lends itself to ease in assembling or disassembling.

The portions of the control lines extending 65 along and adjacent to the fittings 4 are protected by removable shields 45, as shown particularly in Figs. 3 and 6. The edges of the shields conform to the faces of the fittings and 70 are provided with ears 46. Screws or bolts 47 pass through these ears and into the body of the fitting. Cutouts are provided in the shields for leading out the control lines 29 and 36 at the several nozzle fittings.

5 The control lines and their protective coverings obviously move with the standpipe when it is being rotated. A novel form of bearing 10^a has been devised to permit of the necessary support and easy rotation of the standpipe and its associated parts. As illustrated in Fig. 1, these bearing plates are located at each floor level, and their detail construction is shown in the lower part of Fig. 2 and in Fig. 5.

10 A plurality of brackets 50 are welded or otherwise secured to the standpipe. Each bracket 50 carries a roller 51 which engages the inner surface of a flanged annulus 52 secured to the floor. The brackets 50 are spaced apart in order to provide ample room for the protection tubes 42 and the control lines to pass between them. A cover plate 53 rests on the annulus 52 and is free to rotate with the standpipe and the protective enclosures 42 which pass through it and which are closely surrounded by the edges of the openings of the cover plate.

15 As the lower parts of the control lines emerge from the lowermost protective sleeves 42 some of them are coiled partway around the standpipe, as shown in Fig. 9, to connect with their respective valves 37 , which in turn are connected with the interior of the standpipe as illustrated in Fig. 10. It is very desirable to afford protection means for the control lines at this point.

20 For this purpose a bell-shaped housing 55 is provided. This housing is made in segmental form for purposes of assembly and so that any of the segments can be separately removed for inspection or repair of the control lines. The protective sleeves 42 being extended downward to the housing 55 , the control lines are covered for substantially all their length, only the control valves 37 being exposed. The valves and their adjoining exposed connections can be made of a more rugged construction than the light weight pipe used in the control lines.

25 Reference will now be had to Figs. 7 to 12, in which similar parts to those described heretofore bear like reference numerals with the super-character a . The parts illustrated and described in connection with Figs. 9 and 10 are common to that form of the invention heretofore described and to the form of the invention now about to be described.

30 As before, the standpipe 2^a comprises pipe sections 3^a joined together by nozzle fittings 4^a and an operating station fitting 5^a . A lever 13^a may be provided for manually turning the standpipe. In addition to turning the standpipe means are provided in this form of the invention for moving the standpipe vertically. This means may be varied, and as illustrated a hydraulic cylinder 60 such as disclosed in my prior patents is used.

35 The nozzles 15^a are arranged to be oscillated in a horizontal plane relatively to the standpipe instead of vertically. The means for accomplishing this are particularly illustrated in Fig. 8, where it will be seen that the details of construction are quite similar to those heretofore described, with the exception of the parts being disposed in a plane at substantially right angles to that shown in Figs. 1 to 6. Arranging the nozzles in this manner secures a maximum coverage by the streams and enables nozzles at different levels to be turned in different lateral directions independently of each other. The standpipe may or may not be turned. Hose valves 21^a , similar to valves 21 , are secured to extensions 20^a from the branches 14^a .

40 A somewhat modified form of bearing member 10^a is shown in connection with this form of the invention though it is equally applicable to the other form. A flanged ring 70 is secured to the floor. The upstanding flange of this ring has an annular groove 71 which is engaged, but not tightly, by the ends of set-screws 72 . The set-screws 72 are carried in an annular skirt 73 depending from a plate 74 . The plate 74 has apertures through which the protecting sleeves 10 42^a pass freely but closely and a central aperture 75 through which the standpipe passes. Ball bearings 76 are provided in the plate 74 for contact with the standpipe.

45 When the standpipe is turned the protecting sleeves 42^a are carried with it and the set-screws 72 move in the groove 71 . When the standpipe is moved vertically the ball bearings 76 permit of a free and easy movement and the set-screws 72 engaging the groove 71 prevent any vertical displacement of the parts of the bearing.

50 From the foregoing description and an inspection of the drawings it is thought that the operation of the invention will be apparent.

55 Since numerous changes may be made in the forms of the invention which have been described and other forms may be readily devised, it will be understood that the foregoing description is to be considered as being illustrative and not limiting.

30 I claim:

1. In a standpipe system for buildings, the combination of a standpipe to which fluid under pressure is supplied, fittings at spaced intervals in said standpipe, a remote control nozzle valve 35^a in each fitting, a nozzle carried by each fitting, a hose valve associated with each fitting, each nozzle valve in one position shutting off the supply of fluid to said nozzle and in another position shutting off the supply of fluid to said hose valve, 40 and means for selectively operating said nozzle valves from a common control station, whereby when a nozzle valve at any level is thus opened loss of pressure for discharging the nozzle stream is prevented even though the corresponding hose valve has been left open.

2. In a standpipe system for buildings, the combination of a standpipe to which fluid under pressure is supplied, fittings at spaced relations in said standpipe, a nozzle on each fitting, a double-faced valve mounted on each fitting, a fluid pressure actuated piston for moving said double-faced valve, a valve seat on either side of said double-faced valve, a manually operated hose valve in each fitting, said double-faced valve 50 when cooperating with the seat at one side closing communication between the nozzle and the standpipe, and when cooperating with the seat at the other side closing communication between the hose valve and the standpipe, and control lines passing from said fluid-actuated pistons to a common control station and there provided with respective control valves, whereby when a nozzle valve at any level is opened from the control station an adequate fire-extinguishing stream will be delivered from the nozzle even though the corresponding hose valve has been left open.

3. In a standpipe system for buildings, the combination of a movable standpipe having nozzle fittings at different levels, a fluid actuated valve in each fitting, grouped control lines extending from said valves along the outside of the standpipe to a control station, a sectional enclosure for said grouped control lines, and detachable 75

connections securing sections of said enclosure to said nozzle fittings.

4. In a standpipe system for buildings, the combination of a standpipe having nozzle fittings at intervals, a fluid-actuated valve in each fitting, grouped control lines extending from said valves along the outside of the standpipe to a control station, shields applied to the nozzle fittings to cover the grouped control lines where they extend 10 along the fittings, detachable connections securing said shields to said fittings, and other shields enclosing the control lines between the fittings.

5. In a standpipe system for buildings, the combination of a standpipe having nozzle fittings at intervals, a fluid actuated valve in each fitting, grouped control lines extending from said valves along the outside of the standpipe to a control station, shields applied to the nozzle fittings to cover the grouped control lines where they extend 15 along the fittings, sleeves enclosing the control lines between the fittings, detachable connections securing said shields to said fittings, and slip connections for securing said sleeves.

6. In a standpipe system for buildings, the combination of a vertically movable and rotatable standpipe having nozzle branches at different levels, fluid-actuated means associated with said nozzle branches, control lines passing from said fluid-actuated means along the outside of the 20 standpipe to a control station, and bearings for said standpipe, each of said bearings comprising a floor-plate and a rotatable part which turns on the floor-plate with the standpipe and in which the standpipe is vertically movable, said rotatable 25 part having openings through which said control lines pass, and anti-friction members between the standpipe and said rotatable part.

7. In a fire-extinguishing standpipe system for buildings, the combination of a nozzle and a nozzle valve carried by the standpipe, a hose connection and a hose valve likewise carried by the standpipe and in the same general vicinity with said nozzle and nozzle valve, remote control means for operating said nozzle valve from a station 40 away from the heat zone of a fire in the space protected by said nozzle and nozzle valve and said hose connection and hose valve, and means for automatically shutting off communication between the hose valve and the standpipe when 45 opening of the nozzle valve is brought about by said remote control means.

8. In a fire-extinguishing standpipe system for buildings, the combination of a nozzle and a nozzle valve carried by the standpipe, a hose connection with a hose valve likewise carried by the standpipe and in the same general vicinity with said nozzle and nozzle valve, and remote control 50 means operable from a station away from the heat zone of a fire in the space protected by said nozzle and nozzle valve, to open said nozzle valve and simultaneously shut off communication between said hose valve and the standpipe.

9. In a fire-extinguishing standpipe system for buildings, the combination with the standpipe, of nozzles and nozzle valves carried by the standpipe at different levels, hose connections and valves likewise carried by the standpipe to protect the same regions as the nozzles and nozzle valves, connections passing from the several nozzle valves to a common control station to effect 60 selective opening of any one or more of said nozzle valves, and means controlled by the same connections to effect the shutting off of com-

munication between the corresponding hose valve or hose valves and the standpipe.

10. In a fire-extinguishing standpipe system for buildings, the combination with the standpipe, of nozzles and nozzle valves carried by the standpipe at different levels, hose connections and valves likewise carried by the standpipe to protect the same regions as the nozzles and nozzle valves, fluid-pressure devices associated with the several nozzle valves, fluid control lines passing from said fluid pressure devices to a common control station where said lines are provided with control valves operable to bring about opening of any one or more of said nozzle valves, and means for automatically shutting off communication between a hose valve or hose valves and the standpipe when opening of the neighboring nozzle valve or nozzle valves is effected as the result of operation of the corresponding control valve or control valves at the control station. 15

11. In a fire-extinguishing system for buildings, the combination of a movable standpipe having nozzles and fluid-actuated nozzle valves at different levels, fluid control lines passing from the several fluid-actuated nozzle valves to a common control station, said fluid control lines being collected together in a compact group extending along the outside of the standpipe, a protective enclosure for said control lines, said enclosure being eccentric to the standpipe and assembled 20 with the standpipe to move therewith, and floor bearings through which the standpipe passes, said bearings being constructed and arranged to afford lateral support direct to the standpipe and to accommodate said enclosure. 25

12. In a fire-extinguishing system for buildings, the combination of a movable standpipe having nozzles and fluid-actuated nozzle valves at different levels, fluid control lines passing from the several fluid-actuated nozzle valves to a common control station, said fluid control lines being collected together in a compact group extending along the outside of the standpipe, a protective enclosure for said control lines, said enclosure being eccentric to the standpipe and assembled 40 with the standpipe to move therewith, and floor bearings through which the standpipe passes, said bearings being constructed and arranged to afford lateral support direct to the standpipe and to accommodate said enclosure, said bearings having plates with openings closely surrounding said standpipe and said enclosure to prevent flue action through the bearings. 45

13. In a fire-extinguishing system for buildings, the combination of a movable standpipe 55 having at different levels movable nozzles, fluid-actuated nozzle valves and fluid-actuated devices for moving the nozzles relatively to the standpipe, fluid control lines passing from the several fluid-actuated valves to a common control station, 60 other fluid control lines passing to the control station from the several fluid-actuated devices for moving the nozzles, the control lines for the two purposes being segregated in separate compact groups extending along the outside of the 65 standpipe, separate enclosures for said groups of control lines, said enclosures being eccentric to the standpipe and assembled with the standpipe to move therewith, and floor bearings through which the standpipe passes, said bearings being 70 constructed and arranged to afford lateral support direct to the standpipe and to accommodate said enclosures.

WILLIAM F. CONRAN.
